PHOTOGRAPHIC PRINTING AND DEVELOPING APPARATUS

Patrick P. Howrilka, Endwell, N.Y., assignor to General Aniline & Film Corporation, New York, N.Y., a corporation of Delaware

Filed Nov. 4, 1959, Ser. No. 58,203

Term of patent 14 years

(Cl. D61—1)

FIG. I

FIG.2

FIG.3

Figure 1 is a perspective view of a photographic printing and developing apparatus, showing my new design, the opposite side being substantially a mirror image thereof;

Figure 2 is a top plan view; and

Figure 3 is a front elevational view thereof.

The back, not shown, is conventional.

I claim:

The ornamental design for a photographic printing and developing apparatus, substantially as shown and described.
